UNITED STATES PATENT OFFICE.

WILLIAM G. KRANZ, OF SHARON, PENNSYLVANIA, ASSIGNOR TO THE NATIONAL MALLEABLE CASTINGS COMPANY, OF CLEVELAND, OHIO, A CORPORATION OF OHIO.

GAS-FIRED MELTING-FURNACE.

1,067,040.

Specification of Letters Patent.

Patented July 8, 1913.

Application filed October 16, 1908. Serial No. 458,053.

To all whom it may concern:

Be it known that I, WILLIAM G. KRANZ, of Sharon, in the county of Mercer and State of Pennsylvania, have invented a new 5 and useful Improvement in Gas-Fired Melting-Furnaces, of which the following is a full, clear, and exact description, reference being had to the accompanying drawings, in which—

10 Figure 1 is a vertical longitudinal section of a furnace constructed in accordance with my invention; Fig. 2 is a horizontal section partly in plan view on the irregular line II—II of Fig. 1; Fig. 3 is a vertical section 15 on the line III—III of Figs. 1, 2 and 6; Fig. 4 is a vertical section on the line IV—IV of Figs. 1, 2 and 6; Fig. 5 is a vertical section on the line V—V of Figs. 1 and 2; and Fig. 6 is a vertical section on the line 20 VI—VI of Fig. 3.

The purpose of my invention is to provide a furnace for the efficient melting of 25 pig iron for use in the manufacture of malleable castings, which operation must be carried on with uniformity, so as to produce a regular and uniform product of castings, and for this reason a proper construction of 30 furnace is of great importance. My furnace has proved very efficient for these purposes.

In the drawings, 2 represents the hearth 35 of the melting furnace having a reverberatory roof 3, as shown, and 4 is a gas producer chamber, which is built directly at the front end of the furnace, with its discharge flue 5 discharging the gases directly 40 into the furnace throat.

6 is the hopper of the producer, and 7 are 45 the blower-pipes. At the rear end of the furnace between the end of the hearth and the stack flue 8 is a recuperator chamber 9, divided by vertical partition 10 into two or more sub-chambers 9^a and 9^b, through which the waste gases from the furnace pass serially on their way to the stack as indicated 50 by dotted arrows in Fig. 1. In this recuperator are a series of transverse flues preferably built of tile. I show them arranged in four series 11, 11^a, 11^b and 11^c, which 55 communicate at their ends with passages 12^a, 12^b and 12^c at one end of the recuperator and 12^d and 12^e at the opposite end of the recuperator. These passages are separated from each other by the vertical partition 10 and the horizontal partitions 13,

13^a and 13^b, so that the air which is admitted through the inlet 14 into the chamber 12^a passes to the chamber 12^b through the recuperating flues 11; thence to the passage 12^c through the recuperating flues 11^c, 60 thence to the passage 12^d at the other end of the recuperator through the recuperating flues 11^d, and thence similarly through the recuperating flues 11^e, thence downwardly through the passage 12^e into an air flue 14^a, 65 by which it is conducted to the air inlet ports 15, and emerging from said ports, the now heated air mixes with the producer gases from the producer port 5 and supports the combustion thereof. 70

As the air is expanded in its passage through the recuperator flues, I prefer to make the groups of flues successively larger or greater in number. Thus, in the group 11, I show five flues; in the group 11^a, six 75 flues; in the group 11^b, seven flues; and in the group 11^c, ten flues. These flues being highly heated by the waste gases passing through the recuperator on their way to the stack, give up the heat to the air, which is thus delivered to the furnace in a heated condition and enhances the combustion of the producer gas. I am enabled in this way to run the furnace with much less fuel than heretofore, and also to produce more 80 uniform heating effect than has heretofore been possible in the operation of such furnaces. 85

The construction is very compact and convenient, the recuperator being introduced 90 directly between the rear end of the furnace and the stack and the producer chamber being built in close proximity to the front end of the furnace. My invention also possesses 95 many advantages in that it enables me to procure a better molten product for the manufacture of malleable castings than can be obtained from the ordinary coal-fired reverberatory furnace, and at a less cost of melting than with an open hearth furnace. 100

By reconstructing the furnace with recuperator chambers and using gaseous fuel I get a furnace which gives more intense heat than a reverberatory coal-fired furnace, 105 costs less to construct than the open hearth furnace and will afford much of the efficiency which can be had otherwise only with the open hearth. Where coal is burned directly in a reverberatory furnace the iron cannot be brought to the proper tempera- 110 /

ture without skimming off the slag and subjecting the iron to a hot flame under forced draft. This endangers the quality of the iron not only because of the rapidly oxidizing nature of the flame, but also because the strong blast conveys a large amount of sulfur and ash from the coal to the iron, the iron not being protected by the slag. In the use of my furnace so intense is the heat and so uniformly distributed over the surface of the iron, that the slag can be left on the iron as a protection from the sulfur contained in the flame until the iron is all tapped out of the furnace, and yet the iron can be properly reduced and brought to a proper state of fluidity in as short a time as in a reverberatory furnace where the slag is skimmed off.

With my furnace a manufacturer can retain approximately the same melting capacity as with the coal-fired reverberatory furnace, and distribute the furnaces in the same way, and get the benefits of the open hearth furnace with a furnace costing less to build and easier to operate, and in one respect get a result which could not be obtained with the open hearth furnace. In the open hearth the gas is reversed from time to time during the refining process so as to heat the incoming gas and air by means of the checker work which has been heated by the outgoing burning gases, but as long as the gas and air are entering through the chamber on one side that chamber is being cooled off and when the gas is again reversed it starts through the other chamber at its maximum temperature, so that the temperature of the incoming gas and air fluctuates considerably. In my furnace the air is heated by continuously passing through the same series of flues and is gradually increased in temperature from the start until it reaches its maximum, and is not subject to the fluctuations of the open hearth. This is advantageous in giving uniformity to the molten metal produced by the furnace. An-

other advantage in this furnace over the old reverberatory furnace is that the recuperator, by removing a large amount of heat from the outgoing gases in order to heat the incoming air, reduces the heat conveyed to the stack so largely that the life of the stack is greatly increased. Another is that the nature of the flame can be controlled by changing the amount of steam supplied to the producer or the amount of air admitted to the furnace so that the flame can be changed from reducing to oxidizing or vice versa much more readily and accurately than in the reverberatory furnace.

Within the scope of my invention, as defined in the claim, modifications may be made, since what I claim is:

A gas-fired melting furnace having a recuperator chamber beyond its exit end and between the furnace and the stack, a transverse partition wall extending upwardly within the recuperator chamber toward its upper end to give the gases up and down passes therethrough, a plurality of passages at each end of the recuperator chamber separated from each other, groups of air flues extending transversely through the recuperator compartments, the first group being located adjacent to the stack and the last group being located adjacent to the opening from the furnace to the recuperating chamber, the passages and groups of flues being arranged to give the air a serial passage through successive groups of the flues, and a return passage for the heated air leading rearwardly to the gas inlet end of the furnace, the successive groups of air flues being arranged to give increased area to the flow of air.

In testimony whereof, I have hereunto set my hand.

WILLIAM G. KRANZ.
